CLAIM

The ornamental design for a cap for a bottle, as shown and described.

DESCRIPTION

FIG. 1 is a top perspective view of a cap for a bottle;
FIG. 2 is a bottom perspective view thereof;
FIG. 3 is a bottom view thereof;
FIG. 4 is a top view thereof;
FIG. 5 is a left side view of the cap for a bottle with the right
side being a mirror image thereof;
FIG. 6 is a cross sectional view taken in the direction of line
6-6 on FIG. 5; and,
FIG. 7 is an enlarged top view taken from within portion 7
on FIG. 4.

The broken lines show portions of the design that form no
part of the claimed design.
The dot-dash broken lines represent the designation of an
enlargement view and form no part of the claimed design.
